UNITED STATES PATENT OFFICE.

DOUGLAS F. FESLER, OF CHICAGO, ILLINOIS, ASSIGNOR TO ALEMITE MANUFACTURING CORPORATION, OF CHICAGO, ILLINOIS, A CORPORATION OF DELAWARE.

LUBRICANT COMPRESSOR.

Application filed April 27, 1923. Serial No. 634,935.

My invention relates to improvements in lubricant compressors, and is particularly concerned with the provision of a lubricant compressor adapted to form part of a lubricating system comprising a plurality of fittings or nipples to be secured to bearings to be lubricated, and a compressor for successively supplying lubricant under high pressure to said nipples or fittings.

10 The objects of my invention are

First. To provide a compressor of the character described, by means of which the lubricant delivered to the fittings can be placed under high pressure by the use of one hand, thereby leaving the other hand free to manipulate the coupling for successively making connection with the various fittings;

15 Second. To provide a compressor of the character described comprising a low pressure cylinder of comparatively large capacity, and a high pressure cylinder adapted to receive lubricant from the low pressure cylinder and deliver it to the fittings under high pressure, in combination with means whereby a single force will place the lubricant in both of said cylinders under pressure;

20 Third. To provide a compressor such as described in which the priming of the high pressure cylinder by the low pressure cylinder is automatically accomplished, and

25 Fourth. To provide a compressor such as described which is simple in construction, economical to manufacture, and easy to operate.

Other objects will appear as this description progresses, reference being had to the accompanying drawings, in which

30 Figure 1 is a vertical longitudinal section;

35 Figure 2 is a transverse section taken on line 2-2 of Figure 1, and

Figure 3 is a central longitudinal section through a coupling member which may be used as a part of my compressor.

40 The embodiment of my invention disclosed herein comprises a low pressure cylinder 5, in which is mounted a piston comprising the follower plate 6, the two cup leathers 7 and 8, which are arranged with their bottoms in opposed relation on opposite sides of the follower plate 6, and the two face plates 9 and 10 which are mounted in the bottoms of the cup leathers 7 and 8. These elements are all secured to the inner end of the piston rod 11, which is reciprocably mounted in a

sleeve 12 threaded into a central opening in the end 13 of the low pressure cylinder. The outer end of this piston rod is suitably bent or curved to provide a foot 14 for resting upon the ground or any other suitable support. If desired, a stop 15 may be secured to the piston rod, by means of the set screw 16, for limiting the inward movement of the piston. I have shown the spring 17 interposed between the piston and the end 13 of the low pressure cylinder, and tending to urge the piston inwardly. I also provide the end 13 of the cylinder 5 with an opening 18 to permit atmospheric pressure to be exerted upon the outer face of the piston.

45 The open end of the low pressure cylinder 5 is threaded into the cap 19 so that it can be removed therefrom for the purpose of filling the low pressure cylinder.

50 The cap 19 is provided with a laterally extending bracket 20 which supports the vertically disposed high pressure cylinder 21. This cylinder communicates with the low pressure cylinder 5 through the passageway 22 extending through the bracket. The lower end of the high pressure cylinder 21 terminates in a valve chamber 23, the lower end of which is closed by the threaded plug 24. A check valve 25 formed of a disc of fibre, the sides of which are flattened, as shown at 26, is slidably mounted in the valve chamber, and seats against the shoulder 27 at the outer end of the high pressure cylinder. A compression spring 28 interposed between the check valve 25 and the plug 24 tends to yieldingly hold this valve on its seat.

55 A plunger 30 is slidably mounted in the high pressure cylinder and the hollow boss 31, the bore of which registers with the bore of the high pressure cylinder 21. For reciprocating the plunger 30, I provide the bracket 32, which extends outwardly from the high pressure cylinder and on which is pivotally mounted a pair of links 33 (only one of which is shown), the upper ends of which carry the pivot pin 34 on which is pivotally mounted the lever 35. This lever is provided with a terminal projection 36 having a cross-head 37 adapted to contact with the links 33 to limit the upward movement of the lever 35. The opposite end of the lever 35 is provided with a handle 38 which is preferably positioned substantially in alignment, that is, directly above the low pressure cylinder 5, so that the handle 38

may be used for carrying the entire compressor.

The upper or outer end of the plunger 30 is provided with a cap 39 having a pair of spaced lugs 40 for receiving an intermediate portion of the lever 25. These lugs are pivotally connected with the lever by means of the pivot pin 41.

A compression spring 42, interposed between the bracket 20 and the cap 39 and surrounding the boss 31, yieldingly urges the plunger 30 in an outward direction. In the uppermost position of this plunger, its lower end raises to a position which permits the lubricant to pass from the passageway 22 into the high pressure cylinder.

The valve chamber 23 is provided with a flexible discharge conduit 43 which ends in a coupling member comprising the sleeve 44 which is swiveled upon the member 45. The member 45 is soldered or otherwise secured to the free end of the conduit 43, and is secured to the sleeve 44 by means of a second sleeve 46. The sleeve 44 has a valve seat 47 therein through which the stem 48 of the valve 49 projects. A tension spring 50 is interposed between the inner end of the valve and a cup leather 51 which seals the joint between the sleeve 44 and the member 45. This spring tends to yieldingly hold the valve 49 on its seat. Another cup leather 52 is slidably mounted in the outer end of the sleeve 44 and is adapted to make sealed contact with the end of a fitting 53 when the sleeve is passed over the end of the fitting, as shown in Figure 3. A compression spring 54, interposed between the cup leather 52 and the valve seat 47, yieldingly urges the cup leather 52 in an outwardly direction, and consequently tends to assist the valve 50 to maintain the valve 49 in its closed position.

The details of construction of the coupling member just shown form no part of my present invention, except as they co-act with the remaining elements described above. I have disclosed this type of coupling member because I prefer to use one containing a valve which automatically opens when a connection is made with a fitting, and which automatically closes when this connection is broken. My invention, however, is not limited to use with this type of coupling member, as it may be used with a coupling member which does not embody a valve.

In the use of my improved compressor, the barrel 5 is first unthreaded from the cap 19. The operator then pulls upon the piston rod 11 until the piston is moved to a position adjacent the closed end of the cylinder 5 where it is held by means of the adjustable stop 15. The cylinder can then be filled with lubricant and screwed back into the cap 19. The stop 15 is then moved downwardly to a position which will not interfere with the operation of the piston. The operator then con-

nects the coupling member with a fitting for receiving lubricant, and places the foot 14 of the compressor upon the ground, or some other suitable support. Then by oscillating the handle 38, the lubricant can be pumped from the low pressure cylinder through the high pressure cylinder and out through the discharge conduit 43 into the fitting. The pump construction described is such that it forms a complete vacuum in the high pressure cylinder and prevents the return of any lubricant or air to the high pressure cylinder, so that even though the lubricant in the low pressure cylinder has air entrapped therein, the pump is, nevertheless, capable of supplying lubricant under high pressure to the fittings.

It will be apparent that the foot 14 acts as a support for re-acting against the pressure exerted upon the handle 38. When this pressure or force is released, the spring 42 tends to move the plunger 30 outwardly, and the spring 17 tends to push the plunger in the low pressure cylinder inwardly. This action of the spring 17 is supplemented by atmospheric pressure exerted on the outer face of the piston in the low pressure cylinder 5, and, as a matter of fact, atmospheric pressure alone is usually sufficient to move this piston inwardly so that, if desired, the spring 17 may be dispensed with under most circumstances. The downward pressure upon the handle 38 will, of course, tend to move the piston inwardly in the low pressure cylinder, but in this position the plunger 30 is so located that it prevents the lubricant in the low pressure cylinder from being forced into the high pressure cylinder, but as soon as the pressure on the handle 38 is relieved, the plunger moves outwardly, and permits the high pressure cylinder to be primed from the low pressure cylinder.

While I have described the details of construction of the preferred embodiment of my invention, it is to be clearly understood that my invention is not limited to these details, but is capable of other adaptations and modifications within the scope of the appended claims.

Having thus described my invention, what I claim is:

1. A lubricant compressor comprising a low pressure cylinder having a piston slideable therein, a piston rod secured to said piston and extending outwardly through the lower end of said low pressure cylinder, a spring for urging said piston inwardly, a cap for the upper end of said low pressure cylinder having a laterally extending bracket a vertically disposed high pressure cylinder carried by said bracket, said bracket having a passageway for establishing communication between said low pressure and said high pressure cylinders, a discharge conduit for said high pressure cylinder, a check valve in-

- terposed between said discharge conduit and said high pressure cylinder, a plunger slideable in said high pressure cylinder, a link pivotally mounted upon said bracket outward beyond said high pressure cylinder, a lever having one end pivotally mounted on the upper end of said link, the free end of said lever being provided with a handle positioned over said low pressure cylinder, a pivotal connection between said plunger and said lever, and a spring for urging said plunger upwardly. 5
2. A lubricant compressor comprising a low pressure cylinder having a piston slideable therein, a piston rod secured to said piston and extending outwardly through the lower end of said low pressure cylinder, a cap for the upper end of said low pressure cylinder having a laterally extending bracket, a high pressure cylinder carried by said bracket, said bracket having a passageway for establishing communication between said low pressure and said high pressure cylinders, a discharge conduit for said high pressure cylinder, a plunger slideable in said high pressure cylinder and means movable toward said piston for reciprocating said plunger. 10
3. A lubricant compressor comprising a low pressure cylinder having a piston therein, a piston rod connected with said piston and extending through the lower end of said low pressure cylinder, the outer end of said piston rod being provided with a foot for resting upon a suitable support, a high pressure cylinder communicating with said low pressure cylinder and manually operable means for placing pressure upon the lubricant in said high pressure cylinder. 15
4. A lubricant compressor comprising a low pressure cylinder, a piston in said low pressure cylinder, a high pressure cylinder communicating with said low pressure cylinder, and a plunger in said high pressure cylinder, said plunger and piston being arranged to move in opposite directions to place pressure upon the lubricant in said compressor, when said plunger is pressed inwardly. 20
5. A lubricant compressor comprising a low pressure cylinder and a high pressure cylinder communicating with said low pressure cylinder, a lubricant displacing element in each cylinder, a spring for moving one of said lubricant displacing elements relatively to said high pressure cylinder, a handle secured to one of said lubricant displacing elements for moving said last named lubricant displacing element against the tension of said spring and for causing the other lubricant displacing element to force lubricant from said low pressure cylinder into said high pressure cylinder. 25
6. A lubricant compressor comprising a high pressure cylinder, a low pressure cylinder communicating with one end of said high pressure cylinder and parallel therewith, a plunger for isolating said high pressure cylinder from said low pressure cylinder and for displacing lubricant from said high pressure cylinder, a lubricant expelling piston in said low pressure cylinder for contacting with the lubricant in said low pressure cylinder throughout substantially its entire length, and common means for causing said piston and plunger to place the lubricant in said cylinders under pressure. 30
7. A lubricant compressor comprising a low pressure cylinder, a piston in said low pressure cylinder, a high pressure cylinder communicating with said low pressure cylinder, a plunger in said high pressure cylinder, said plunger and piston being arranged to move in opposite directions to place pressure upon the lubricant in their respective cylinders, and resilient means for moving said piston and plunger in the same direction. 35
8. In high pressure lubricating apparatus of the class described, a lubricant compressor comprising a low pressure cylinder, a piston in said low pressure cylinder, a high pressure cylinder communicating with said low pressure cylinder, a plunger in said high pressure cylinder, said plunger and piston being movable in opposite directions to place pressure upon the lubricant in their respective cylinders, spring means for advancing said piston, and spring means for retracting said plunger. 40
9. A lubricating compressor, comprising in combination, a pair of lubricant containing chambers, a first one of said chambers adapted to communicate lubricant under pressure to the other chamber, a lubricant discharge nozzle, said other chamber adapted to discharge lubricant under pressure through said nozzle, and common means operable in a single manual lubricant compressing operation to put lubricant in said other chamber under high pressure to force it through said nozzle, and to put the lubricant in the said first chamber under a relatively lower pressure. 45
10. Lubricating equipment comprising portable low pressure compressing means, high pressure compressing means supported by said low pressure means and communicating therewith, and connections for actuating both compressing means by a single manual thrust. 50

In witness whereof, I hereunto subscribe my name this 23rd day of April, 1923.

DOUGLAS F. FESLER.
